US0D1092486S

(12) **United States Design Patent** (10) Patent No.: **US D1,092,486 S**
(45) Date of Patent: ** Sep. 9, 2025

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Haemi Yoon**, Suwon-si (KR); **Youjin Im**, Suwon-si (KR); **Sunghyo Jeong**, Suwon-si (KR); **Sumin Oh**, Suwon-si (KR); **Hongjin Park**, Suwon-si (KR); **Jongkee Lee**, Suwon-si (KR)

(73) Assignee: **Samsung Electronics Co., Ltd.**, Suwon-si (KR)

(**) Term: **15 Years**

(21) Appl. No.: **29/782,336**

(22) Filed: **May 6, 2021**

(30) **Foreign Application Priority Data**

Dec. 21, 2020 (KR) 30-2020-0063646

(51) LOC (15) Cl. **14-04**

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display screen or portion thereof with graphical user interface, as shown and described.

DESCRIPTION

The sole FIGURE is a front view of a display screen or portion thereof with graphical user interface, showing our new design.

The outer perimeter broken line in the drawing represents a display screen or portion thereof and forms no part of the claimed design. The remaining broken lines in the drawing depict portions of the graphical user interface that form no part of the claimed design.

1 Claim, 1 Drawing Sheet
